[57] CLAIM

The ornamental design for a flexible handle for a spray gun, as shown and described.

DESCRIPTION

FIG. 1 is the front elevational view of a flexible handle for a spray gun showing my new design;

FIG. 2 is the rear elevational view thereof;

FIG. 3 is the left side elevational view thereof;

FIG. 4 is the right side elevational view thereof;

FIG. 5 is the top plan view thereof;

FIG. 6 is the bottom plan view thereof; and,

FIG. 7 is the perspective view thereof.

The broken line is for illustrative purposes only and forms no part of the claimed design.

FIG.3

FIG.1

FIG.6

FIG.5

FIG.4

FIG.2

FIG.7
